DOLL TOY

Naoharu Yamashina, 4-14 Komagata 1-chome, Taito-ku,
Tokyo, Japan

Filed June 20, 1974, Ser. No. 481,326

Term of patent 14 years

Int. Cl. D21—01

U.S. Cl. D34—15 AD

FIG. 1

FIG. 2

FIG. 3

FIG.4

FIG.5

FIG.6

FIG. 7

FIG. 8

FIG. 1 is a front view of a doll toy embodying my new design;

FIG. 2 is a rear elevational view;

FIG. 3 is a top plan view;

FIG. 4 is a left side view;

FIG. 5 is a slight perspective view with the head shown in a released position;

FIG. 6 is a bottom plan view;

FIG. 7 is a perspective view of another embodiment with the first part of an arm in released position; and

FIG. 8 is a perspective view thereof with arms in an extended position.

I claim:
The ornamental design for a doll toy, as shown.
